J. H. BOYE

BRACKET AND ROD COUPLING FOR CURTAIN FIXTURES

Filed April 8, 1927

By Fisher, Towle, Clapp & Soans, Atg's.

UNITED STATES PATENT OFFICE.

JAMES H. BOYE, OF CHICAGO, ILLINOIS. ASSIGNOR TO JAMES H. BOYE MANUFACTURING COMPANY, OF CHICAGO, ILLINOIS, A CORPORATION OF ILLINOIS.

BRACKET AND ROD COUPLING FOR CURTAIN FIXTURES.

Application filed April 8, 1927. Serial No. 181,917.

This invention relates to the art of curtain fixtures and has reference more particularly to an improved bracket and rod coupling for curtain rods of the well-known "flat" type, wherein the rod is formed with elbow end portions which telescope over and yieldably interlock with forwardly projecting bracket arms attached to the sides of the window casing. Bracket and rod couplings of this type, wherein the end portion of the rod and the arm of the bracket are formed one with a spring locking member and the other with a recess into which the locking member snaps when the two parts are telescoped are known; and a coupling of this type wherein the transverse elasticity of the rod and its flanges is utilized to effect the locking action is disclosed in a former Patent No. 1,584,354 granted to me on the 11th day of May, 1926.

Rod and bracket couplings of this type have heretofore involved a greater or less degree of lateral looseness or side play between the bracket and the rod when the parts have been coupled, and one object of my present invention is to provide a coupling which will eliminate this side play. Heretofore, also, one result of the spring locking devices has been to more or less cant or tilt the base end of the bracket arm away from the outer or face wall of the rod, thus tending to throw the bracket arm and the portion of the rod that telescopes thereon out of exact alignment. Another object of the invention is to provide an improved bracket and rod coupling which will automatically tend to thrust the base end of the bracket arm toward the outer or face wall of the rod and thus maintain proper alignment of the bracket arm and the end portion of the rod engaged thereby. A still further object of the invention is to provide a construction wherein the transverse elasticity of the locking tongue and the transverse elasticity of the rod and its flanges will cooperate to automatically take up all lateral slack and lost motion between the parts and thereby provide a firm and rigid coupling. A still further object is to provide a construction wherein the transverse elasticity of the rod and its flanges may be utilized to force the locking tongue to quickly snap into its cooperating recess or socket

and continue to engage the latter under its inherent tension.

Still other objects and attendant advantages of the invention will be apparent to persons skilled in the art as the same becomes better understood by reference to the following detailed description, taken in connection with the accompanying drawing 55 60 wherein I have illustrated a practical and preferred embodiment of the invention, and in which—

Figure 1 is a front elevation of an end portion of a flat curtain rod and supporting bracket therefor, embodying the invention.

Figure 2 is a top plan view of Figure 1.

Figure 3 is a horizontal section, enlarged, on the line 3—3 of Figure 1.

Figure 4 is an inner side elevation of the 70 bracket.

Figure 5 is a top plan of the bracket.

Figure 6 is an outer side elevation of the bracket.

Figure 7 is an end elevation of the elbow 75 arm of the rod that telescopes over the bracket.

Figure 8 is a vertical section of the elbow arm of the rod on the line 8—8 of Figure 9.

Figure 9 is an inner side elevation of the 80 elbow end of the rod.

Referring to the drawing, 10 designates a curtain rod of the well-known "flat" type, formed with an integral elbow end portion 11 that telescopes over the forwardly projecting arm of an angle bracket attached to the window casing. Slightly in rear of its extreme end the outer or face wall of the end portion 11 is pressed outwardly, forming a shallow recess or socket 12 having an inclined transverse rear wall 12', best shown in Fig. 9, that cooperates with a spring locking tongue on the bracket, as hereinafter described; and preferably also the extreme end portion of the outer wall, beyond the recess 12, is pressed outwardly, as shown at 13, thereby forming between the recesses 12 and 13 a transverse rib 14, the function of which will hereafter appear. Substantially opposite the rib 14 the inturned flanges 11' 90 of the rod, which possess considerable transverse elasticity, are indented thus forming on said flanges a pair of internal cams 15.

The angle bracket comprises a flat attach-

ing base 16, and a forwardly extending flat arm 17 disposed at a right angle to the base. The outer side of the arm 17, slightly forwardly of the base 16, is indented to form on the opposite or inner side of the arm a low transversely disposed ridge 18, and from the metal of the arm 17 is cut and bent outwardly an inclined spring tongue 19. The free end portion of the tongue is cut out of the outer side wall of the ridge 18, so that the free end or tip of the tongue is slightly bent toward the plane of the arm 17, as shown at 19' in Figs. 3, 5 and 6. In the interlocked position of the parts shown in Fig. 3 this inwardly inclined tip 19' of the tongue bears against the correspondingly inclined transverse wall 12' of the locking recess 12, preventing accidental displacement of the rod from the bracket arm and facilitating the inward camming of the tongue by the rib 14 when the rod is withdrawn from the bracket.

In telescoping the end of the rod over the bracket arm, the rib 14 sliding over the back of the tongue 19 cams the latter inwardly until the hump of the tongue passes the peak of the rib 14, whereupon the tongue snaps into the recess 12 and, at the same time, the tip 19' of the tongue slides down the inclined transverse wall 12' of the recess 12, thus tending to draw the elbow end of the rod to final position on the bracket arm with its extreme end in contact with the base 16. During this operation of telescoping the rod arm onto the bracket arm, the reaction of the spring tongue 19 on the rib 14 draws the cams 15 hard against the opposite side of the bracket arm, so that not only does the tongue 19 bend inwardly but at the same time the cams 15 yield outwardly under the resiliency of the rod and the flanges on which they are formed, so that by the time the rib 14 has passed the hump of the tongue, the spring reaction of the flanges and their cams 15 cooperates with the spring reaction of the tongue to effect the full interlocking of the tongue with its recess and to maintain the tongue in such interlocked position under the inherent tension of both the tongue and the cams, thus effectively preventing any side play or rattle of the rod arm on the bracket arm.

As the tongue snaps into locking position, the cams 15 are drawn hard against the transverse ridge 18 on the inner side of the bracket arm, and this acts to draw the recess into snug engagement with the tongue and at the same time creates a relative side thrust between the base portion of the bracket arm and the inner surface of the front or face wall of the rod arm pressing said parts together, thereby aligning the bracket arm with the rod arm and squaring the bracket base relatively to the rod arm. This latter feature is desirable for the reason that, in

mounting curtain rods of this type, the brackets are often first fitted into the arms of the rod, and are then attached to the window frame by the usual fastening screws.

It will be noted that the described interlocking effects are secured entirely by integrally formed members on the rod and bracket, without the use of attachments. The swell 13 at the end of the front wall of the rod arm is not essential, but is preferably employed to reduce the friction on the back of the tongue as the parts are being telescoped, thus augmenting the ease of the telescoping operation.

I claim—

1. In a bracket and rod coupling for curtain fixtures, the combination of a bracket arm formed with a laterally projecting locking tongue on one side thereof and a transverse ridge on its other side opposite the tip of said tongue, and an end section of a flat curtain rod formed with a recess in its front wall to receive said locking tongue and with elastic inturned flanges on its upper and lower edges, said flanges having indentations adapted to bear under the inherent spring pressure of said rod section and flanges against said ridge.

2. In a bracket and rod coupling for curtain fixtures, the combination of a flat bracket arm formed on one side thereof with a longitudinal outwardly inclined locking tongue having an inwardly bent tip, and a transverse ridge on its other side opposite the tip of said tongue, and an end section of a flat curtain rod formed with a recess in its front wall to receive said locking tongue and with elastic inturned flanges on its upper and lower edges, said flanges having transverse indentations in their free edge portions adapted to bear under the inherent spring pressure of said rod section and flanges against said ridge.

3. In a bracket and rod coupling for curtain fixtures, the combination of a flat bracket arm formed on one side thereof with a longitudinal outwardly inclined locking tongue having an inwardly bent tip, and a transverse ridge on its other side opposite the tip of said tongue, and an end section of a flat curtain rod formed with a recess in its front wall to seat said locking tongue, said recess having an inclined transverse wall against which the inclined tip of said tongue bears, and with elastic inturned flanges on its upper and lower edges, said flanges having transverse indentations in their free edge portions adapted to bear under the inherent spring pressure of said rod section and flanges against said ridge.

4. In a bracket and rod coupling for curtain fixtures, the combination of a flat bracket arm formed on the outer side thereof with a longitudinal outwardly inclined spring locking tongue having an inwardly

bent tip, and a transverse ridge on its other side opposite the tip of said tongue, and an end section of a flat curtain rod formed with a locking recess in its front wall to receive said locking tongue, an end recess in its front wall forming with said locking recess a transverse rib over which the back of said spring

tongue slides as the parts are telescoped, and with elastic inturned flanges on its upper and lower edges, said flanges being indented there under the inherent spring pressure of said rod section and flanges against said ridge. ¹⁰

JAMES H. BOYE.
